CONVERTIBLE SKIRT AND CULOTTE

Leonard Wolman and Harry Deutsch,
Chicago, Ill.

Application June 14, 1941, Serial No. 397,998

1 Claim. (Cl. 2—213)

Our present invention relates to the provision of a garment of the skirt-culotte type. It should be borne in mind that while the names skirt and culotte cover quite a number of differently designed garments, the present styles require these respective forms of garments to be made with neatness and elegance and without suggestion of convertibility. In other words, it distinctly detracts from the appearance of the skirt for it to bear evidence that it can be transformed into a bifurcated or divided garment and the present style of culotte requires the leg portion to hang as nicely as a well designed skirt, with suitable provision for a crotch portion which does not pull or distort the other portions of the garment or cause the wearer discomfort.

We have accomplished the provision of a convertible garment in which, when in skirt form, the inverted plaits and all other portions of the skirt hang from the belt, and which in culotte form provides an ample crotch which does not need to and which does not absorb any portion of the exterior of the garment in providing the crotch forming material. The conversion either from skirt to culotte or from culotte to skirt may be easily effected while the garment is being worn. It is, therefore, apparent that the object of our invention is to provide a convertible garment of the skirt-culotte type which is an improvement upon, and has certain inherent advantages over, previously designed convertible garments of the same general character.

We have attained the foregoing objects by means of the structure illustrated in the accompanying drawing in which

Fig. 1 is a front elevation of a convertible garment embodying our invention;

Fig. 2 is a vertical or longitudinal section of the garment looking toward the garment front and showing the interior of the construction of the front of the garment;

Fig. 3 is a vertical or longitudinal section looking toward the rear of the garment and showing the arrangement and construction of the interior of the rear of the garment;

Fig. 4 is an horizontal section taken on the line 4—4 of Figure 1 and showing the garment in skirt form; and

Fig. 5 is a similar horizontal section but showing, however, the garment in culotte form.

A garment embodying our present invention is formed of fabric or any other suitable flexible material and may have as many vertical panels as the tailor may deem necessary or desirable for securing the desired shape and style. However, the requisites for securing convertibility as herein described and illustrated, are two front exterior panels, 10 and 11, two rear exterior panels, 12 and 13, a front intermediate interior panel 14, and a rear intermediate interior panel 15. 60

The upper margins of the front and rear panels are stitched or otherwise suitably secured to a belt which, as shown in Figure 1 of the drawing, is adapted to surround the waist of the wearer 5 of the garment. The front exterior panels 10 and 11 are disposed in side by side relation and have the inner side margins thereof inwardly doubled back to form infoldments 10a and 11a. The rear exterior panels 12 and 13 are disposed 10 directly behind the front exterior panels 10 and 11, respectively, and have their inner side margins inwardly doubled back to form infoldments 12a and 13a. When the garment is in skirt form 15 the front intermediate internal panel 14 is disposed directly behind the infoldments 10a and 11a and forms therewith an inverted plait. The folds of the front panels 10 and 11 are normally disposed in close proximity with one another when the garment is worn and have the upper 20 portions thereof stitched together and to the upper portion of the center line of the front intermediate interior panel 14 by stitching 16. The latter, as shown in Figures 1 and 3, extends downwards from the belt to a point adjacent the 25 crotch of the wearer of the garment. The free side edge of the infoldment 10a of the front panel 10 is stitched to the adjacent side edge of the front interior panel 14 by stitching 17. The lower portion of the free side edge of the infoldment 11a and the adjacent side edge of the interior panel 14 are separate from one another 30 and are in effect slit, the slit extending from the bottom of the garment to a point adjacent the lower end of the stitching 16. A hookless or 35 slide type fastener 22 of the "Zipper" or "Talon" type is applied to the slit edges of the infoldment 11a and the front interior panel 14 and serves when the garment is in skirt form to connect such edges together. The front plait is provided with transverse stitching 19a and this leads 40 inwards from the upper end of the slit in the front plait to the longitudinal center line of the front intermediate panel 14 and serves to connect the portion of said panel 14 that is immediately 45 inwards of the upper end of the slit to the contiguous portion of the infoldment 11a. The part of the front plait that is directly above the stitching 19a is provided with a transverse cut 19 and this extends inwards from the upper end of the 50 slit to a point adjacent the inner end of said stitching 19a. A hookless or slide type fastener 20 serves to secure together the cut edges of the front plait when the garment is used as a skirt. 55 When the garment is in its skirt form and the fastener 20 is closed such fastener serves to hold in place the lower portion of the infoldment 11a and serves to prevent such portion from sagging and thus distorting the front plait. The slide part of the fastener 22 is adapted to run or be

slid upwards to effect opening of the slit in the front plait. The slide of the fastener 20 is adapted to run or be slid inwards from the upper end of the slit in the front plait to the inner end of the cut 19 in connection with release of said fastener 20. When the garment is in skirt form the fasteners 22 and 20 are closed with the result that the inverted plait in the front of the garment is completed so far as form is concerned.

The folds of the rear exterior panels 12 and 13 are normally disposed in closed proximity to one another when the garment is worn and have the upper portions thereof stitched together and to the upper portion of the center line of the rear intermediate interior panel 15 by stitching 16a. The latter, as shown in Figure 3, extends downwards from the garment belt to a point adjacent the crotch of the wearer of the garment. The free side edge of the infoldment 13a of the rear panel 13 is stitched to the adjacent side edge of the rear interior panel 15 by stitching 18. The lower portion of the free side edge of the infoldment 12a and the adjacent side edge of the interior panel 15 are separate from one another and are in effect slit, the slit extending from the bottom of the garment to a point adjacent the lower end of the stitching 16a. A hookless or slide type fastener 23 of the "Zipper" or "Talon" type is applied to the slit edges of the infoldment 12a and the rear interior panel 15 and serves when the garment is in skirt form to connect such edges together. The rear plait is provided with transverse stitching 21 and this leads inwards from the upper end of the slit in the rear plait to the longitudinal center line of the rear intermediate panel 15 and serves to connect the portion of said panel 15 that is immediately inwards of the upper end of the slit in the rear plait to the contiguous portion of the infoldment 12a. The part of the rear plait that is directly above the stitching 21 is provided with a transverse cut 24 and this extends inwards from the upper end of the slit to a point adjacent the inner end of said stitching 21. A hookless or slide type fastener 25 serves to secure together the cut edges of the rear plait when the garment is used as a skirt. When the garment is in its skirt form and the fastener 25 is closed such fastener serves to hold in place the lower portion of the infoldment 12a and serves to prevent such portion from sagging and thus distorting the rear plait. The slide part of the fastener 23 is adapted to run or be slid upwards to effect opening of the slit in the rear plait. The slide of the fastener 25 is adapted to run or be slid inwards from the upper end of the slit in the rear plait to the inner end of the cut 24 in connection with release of said fastener 25. When the garment is in skirt form the fasteners 23 and 25 are closed with the result that the inverted plait in the rear of the garment is completed so far as form is concerned.

Figures 1 to 4, inclusive show the garment in skirt form with the fasteners 22, 20, 23 and 25 in their closed position. When it is desired to convert the garment to a culotte the fasteners 22 and 23 are forced open. Thereafter, as shown in Figure 5, the lower portion of the free side edge of the front interior panel 14 is connected to the lower portion of the free side edge of the infoldment 12a by the slide of the fastener 22 and

the lower portion of the free side edge of the rear interior panel 15 is connected to the lower portion of the free side edge of the infoldment 13a by the slide part of the fastener 23. After this particular operation the garment is in the form shown in Figure 5. Thereafter the fasteners 20 and 25 are opened so that the portions of the front and rear plaits beneath the cuts 19 and 24 droop and thus accommodate the crotch of the wearer of the garment.

The herein described convertible garment is pleasing in appearance when in skirt form or culotte form. It is simple in design and may be produced at a low cost. In addition, the construction is such that the garment may be converted from one form to the other while being worn.

The invention is not to be understood as restricted to the details set forth since these may be modified within the scope of the appended claim without departing from the spirit and scope of the invention.

What we claim as new and desire to secure by Letters Patent is:

25 A convertible garment of the skirt-culotte type formed of flexible material and comprising when in skirt form a tubular body adapted to extend around and downwards from the wearer's waist and having substantially full length front and rear inverted plaits in the form of infoldments and intermediate interior panels, each of the plaits having one of the inner corners thereof slit upwards from the bottom to a point adjacent the crotch of the wearer of the garment and provided with detachable means for securing the slit edges together when the garment is used as a skirt, also having transverse stitching leading inwards from the upper end of the slit to the longitudinal center line of the intermediate interior panel of the plait and serving to connect together the portion of said intermediate interior panel that is immediately inwards of the upper end of said slit to the contiguous portion of the adjacent infoldment of the plait, and in addition having the part thereof directly above the stitching cut inwards from the upper end of the slit to a point adjacent the inner end of the stitching and provided with detachable means for securing the cut edges together when the garment is used as a skirt, the slits in the two plaits being formed in corners that are diagonally opposite one another, the detachable securing means for the slit edges of the two plaits being adapted to be released in connection with conversion of the garment to a culotte and being so designed and constructed that after release they permit the slit edge of the intermediate interior panel of the front plait to be attached to the slit edge of said adjacent infoldment of the rear plait and the slit edge of the intermediate interior panel of the rear plait to be attached to the slit edge of said adjacent infoldment of the front plait, the detachable means for securing the cut edges of the plaits being adapted to be released in connection with conversion of the garment to a culotte and serving when released to permit the parts beneath the cuts in the plaits to droop for crotch accommodating purposes.
